UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. **7,911**, dated December 1, 1874; application filed November 19, 1874.
[Term of Patent 14 years.]

CASE A.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the casing of a soda-water apparatus, which is of rectangular form, the top *b* being flat. A series of ornamental openings are cut entirely through the sides of the outer shell of the casing A, so as to expose to view the inner shell of the casing, which is composed of different-colored marble, so as to form a contrast; and within each of these openings is placed a tablet, *d*, which is secured to the inner shell of the casing, the marble of which the tablet is composed

being of different color to that of either the inner or outer shell of the casing, three different colors being thus presented to view, and a series of panels, B, of beautiful appearance are thus produced, which render the apparatus exceedingly ornamental. On each side of the upper portion of each panel is an aperture, *f*, which is cut entirely through the outer shell, so as to expose the inner shell to view.

What I claim as my invention, and desire to secure by Letters Patent, is—

The design of the casing A, with its ornamental panels B, substantially as herein shown and described.

Witness my hand this 16th day of November, A. D. 1874.

GEO. F. MEACHAM.

In presence of—

P. E. TESCHEMACHER,
G. A. MEACHAM.
